CLAIM

The ornamental design for a decorative light holder, as shown and described.

DESCRIPTION

FIG. 1 is a top view thereof;

FIG. 2 is a front view thereof;

FIG. 3 is a left side view;

FIG. 4 is a rear view thereof;

FIG. 5 is a right side view thereof;

FIG. 6 is a bottom view thereof; and,

FIG. 7 is a perspective view thereof.

The broken line showing of a light holder stake is for illustrative purposes only and forms no part of the claimed design.
